ATTORNEY.

UNITED STATES PATENT OFFICE.

HERBERT C. HERR, OF DALLAS, TEXAS.

FIRE-HYDRANT CLOSURE.

1,202,289.

Specification of Letters Patent. Patented Oct. 24, 1916.

Application filed August 24, 1915, Serial No. 47,165. Renewed June 14, 1916. Serial No. 103,694.

To all whom it may concern:

Be it known that I, HERBERT C. HERR, a citizen of the United States of America, residing at 2617 Birmingham avenue, Dallas, Dallas county, Texas, have invented certain new and useful Improvements in Fire-Hydrant Closures, of which the following is a specification.

This invention relates to new and useful improvements in quick detachable fire hydrant nipples, caps or closures.

A purpose of the invention is to provide such a device as will facilitate firemen in the quick removal of the nipples from the hydrant prior to connecting up the hose.

A further purpose is to provide a device as mentioned comprising an internally screw threaded cap divided transversely into portions, said portions hinged together and arranged to open and close in a locked relationship.

With the above and other purposes in view, the invention has relation to a certain arrangement and combination of a minimum number of parts as described in the following specification, pointed out in the appended claims and illustrated in the accompanying drawings wherein:

Figure 1 shows the hydrant nipple in plan view. Fig. 2 shows said device pivoted or opened out, the illustration being in side elevation. Fig. 3 is a plan view of the device, parts being removed and a portion broken away. Fig. 4 is a view of a certain swivel and cam member correlated with the invention. Fig. 5 is a bottom view of said swivel and cam member.

Referring now in particular to the drawings, the numerals 1 and 2 designate two associated members pivoted or hinged one upon the other as shown by the numeral 3; said members when folded together form a nipple or cover cap for the protection of the threads on the fire hydrant or plugs which receives the hose connections. The device is screw-threaded for a portion of the distance up its central bore. The member 1 has integrally formed therewith a half disk 4 which projects into a bore 5 formed in the opposite member as shown in Fig. 3. This construction gives a substantial lap of the seam formed by the contact of the two members and insures it against leaking.

An arcuate groove 6 of diminishing width and extending partially around and includ-

ing less than three hundred and sixty degrees is formed in the outside of the plane surface of the assembled device; the said groove having about one-third of its circumferential length or embracing ninety degrees formed in one member, while the remaining portion of the groove is formed in the other member. A pin 7 is integrally formed on one of the members, and in this instance the member 1. A swivel member 8 with an integral wrench head 9 is provided and rotatably confined on the pin. An arcuate cam or flange 10 is integrally formed on the underneath side of the swivel member. Said cam extends about half of the circumference of the swivel member and diminishes in width from one extremity toward the other. The cam is similar in proportion to the groove 6 and is adapted to be rotatably confined in said groove, said cam and groove having a common axis.

With the device open the swivel member will have been so adjusted from the head 9 with a wrench that the cam will lie within the groove in the member 1; when the device is closed upon the fire hydrant and the screw threads have registered with the threads of the hydrant, a wrench will be applied to the head and the cam swiveled about until it has passed into the groove of the opposite member and becomes securely locked and wedged therein. The similar diminishing proportions of the cam and groove insures an increasing tightness and locking security as the cam is forcibly passed into the groove. In unlocking and removing the device from the hydrant, the wrench will be applied and the cam forcibly swiveled back into the member 1 which frees the opposite member to open.

The use of this device saves much time in hose coupling operations. Also its use insures one that the interlocking threads of the nipple and hydrant will not become rusted together and cause injury to the fire plug hydrant threads in unscrewing the old type nipple from the hydrant.

The invention is presented to include all such modifications and changes as may properly come within the scope of the following claims.

Claims:

1. In a hydrant closure, the combination with a screw-threaded member comprising two associated portions pivoted to each other,

of a cam arranged to lock said portions in closed and positive relationship to each other.

2. In a hydrant closure, the combination 5 of a screw-threaded member comprising two associated halves or portions one pivoted to the other, of a groove formed in the plane wall of the member, and a flange adapted to register with the groove and lock the said 10 halves in a closed and positive relation.

3. In a hydrant closure, the combination 15 with a screw-threaded member comprising two associated portions one pivoted to the other, a groove formed in the two members, and a cam carried by one portion adapted 20 to register with the groove and lock the said portions together.

4. In a hydrant closure, the combination 25 with a screw-threaded member comprising two associated halves or portions one pivoted to the other, an arcuate groove formed in said members, said groove being formed of a diminishing width, a swivel member, an arcuate cam or flange formed on said swivel member and adapted to lock the two said halves.

5. In a hydrant closure, the combination 30 with a screw-threaded member comprising two associated portions one pivoted to the other, an arcuate groove formed in the member, said groove extending partially around the circumference which it describes, a swivel member, an arcuate flange formed on the swivel member, said flange extending 35 partially around the circumference which it describes and confined within the groove and adapted to lock the members which comprise the closure.

6. In a hydrant closure, the combination 40 with a cap internally screw-threaded and divided transversely into portions hinged together to open and close as desired, an arcuate groove formed in the cap, a swivel member, an arcuate flange formed on the 45 swivel member and adapted to register with the groove and lock the portions, and a half disk member formed on one of the portions

and adapted to pass into a bore formed in the opposite member thereby covering the seam which is formed by the said associated 50 portions.

7. In a hydrant closure, the combination 55 with a cap internally screw-threaded and divided transversely into portions hinged together, of an arcuate groove formed in the outer plane surface of the cap, of a pin formed on one of the portions, a swivel member rotatably confined on said pin, an arcuate flange formed on the swivel member, said flange and said groove having a 60 common axis, said groove and said flange having their width and thickness gradually decreased from one extremity to the other, the flange rotatably confined in the groove and adapted to lock the portions together. 65

8. In a hydrant closure, the combination 70 with a cap internally screw-threaded and divided transversely into portions hinged together, means provided forlapping or breaking the joint or seam formed by contact of said portions, and means for locking said portions in closed relationship.

9. In a closure cap, the combination with 75 a cap internally screw-threaded and divided transversely into portions hinged together, of a groove formed in one portion, and a movable flange associated with the other portion adapted to pass into said groove.

10. In a closure cap, the combination with 80 a cap internally screw-threaded and divided transversely into portions hinged together, of a web or disk formed on one portion and adapted to lap or break the joint or seam formed by the closed portions, a wrench head confined in a movable relation upon 85 one portion, and locking elements in operative connection with the movable wrench head and adjacent portion.

In testimony whereof, I affix my signature in the presence of two witnesses.

HERBERT C. HERR.
